Peter P. Figueira
Inventor,

By his Attorney James P. Onhamel,

UNITED STATES PATENT OFFICE.

PETER P. FIGUEROA, OF NEW YORK, N. Y.

BATHING-CABINET.

1,330,312.

Specification of Letters Patent.

Patented Feb. 10, 1920.

Application filed June 21, 1916. Serial No. 105,005.

To all whom it may concern:

Be it known that I, PETER P. FIGUEROA, a citizen of the United States, and resident of New York, in the county of New York and 5 State of New York, have invented certain new and useful Improvements in Bathing-Cabinets, of which the following is a specification.

This invention relates to shower baths 10 and more especially to cabinets to contain the same and arranged to be hung at an elevation for the shower to act and to carry a curtain to infold and conceal the bather and prevent the water from splashing 15 beyond a certain range, the outer adjuncts being adapted to be detached and packed in the tank of the cabinet for transportation or storage, as will be more fully described in the following specification, set forth in 20 the claim and illustrated in the drawings accompanying this application, wherein:

Figure 1 is a side elevation of a cabinet with the curtain and tub in section.

Fig. 2 is a front view of the same.

25 Fig. 3 is a vertical sectional view of the cabinet with the bathing attachments packed therein for transportation.

Fig. 4 is a front view of a modified form of cabinet.

30 Fig. 5 is a side view of another form of modification opened for use.

Fig. 6 is a view of the same closed.

Fig. 7 is a view of a ring for carrying the curtain.

35 In localities where there are no modern water supply systems serious difficulties are experienced in providing bathing means and the object of this invention is to provide a simple and compact cabinet which may be 40 quickly turned into a shower bath and is adapted to contain all articles needed in the toilet.

The device consists of a tank 5 preferably 45 made of sheet metal and having a lid 6 held in place by studs 7 at the rear of the tank and the turn-button 8 at the front of the same and whose rotating means is a hook 9. At the bottom of the tank is an outlet nipple 10 and at the front of the tank may be 50 placed a mirror 11 below which is a hook 12, while the tank may have below it a drawer 13 for toilet articles, or the same may be dispensed with and the empty tank itself used to contain all of the attachments 55 and toilet articles.

The upper end of the tank is provided with a bail 14 to carry the same or as a means to suspend the same from some elevation as shown in the drawing.

To convert the device into a shower bath 60 a flexible pipe 15 having an enlarged sprinkler 16 at one end and a cock 17 at the other end, the latter being coupled on the nipple 10 and the sprinkler turned to the horizontal position shown in Figs. 1 and 2 and the 65 handle 18 of the cock may carry a depending chain 19 to open or to close the cock.

A ring 20 carries a curtain 21 by means of small rings 22 which slide around the large ring and allow the opening of said curtain 70 for the entrance of the bather. The ring 20 is supported at one side by the hook 12 and at its outer end by the chain 23 carried by the hook 9 and the lower end of the curtain is inserted in a tub or other receptacle 24 in 75 which the bather may stand when he desires to submit himself to a shower.

The cabinet by itself may be used as a bucket and filled with water at any desired 80 location and carried to the room or place where the bath is to be taken, hung up and the bathing attachments put in place.

It is obvious that an article of this nature is capable of various modifications and in Fig. 4 a cabinet is shown without the drawer 85 for toilet articles and in this case the smaller articles may be deposited with the curtain and pipe within the pipe itself.

In Figs. 5 and 6 the tank is made in the form of a handbag 25 of canvas or leather 90 and is adapted to be hung from a peg by the handle 26. The usual nipple 10 is provided and to the same the pipe 15 is secured while the cock 27 has on its upper side a hook 28 to support the ring 20 at one side and its 95 other side is suspended from a hook 29 on the frame 30 at the mouth of the bag by means of the chain 33. This hook may be used to open or close the bag and at each end of its frame 30 the gores 31 are inserted 100 to retain water at the utmost height.

In the use of such a bag to contain the various attachments the ring 20 may prove too large and in this case it may be divided as shown in Fig. 7 with each half having a 105 socket 32 into which the other end of each section is fitted to complete the ring. It is obvious that means may be provided to close the nipple when the tank or bag is filled preparatory to hanging for use and this will 110

relieve the user of the necessity of carrying the pipe and shower when filling either with water.

The tank may be of any desired ornamental effect and may have hooks 33 at the side for clothing as shown in Fig. 4.

Other arrangements or modifications may be resorted to without departing from the essential features above described or from 10 the scope of the appended claim.

What I claim as new is:

In a bath cabinet the combination with a portable receptacle having carrying and

hanging means and a nipple at its lower side, of a flexible pipe and shower sprinkler, 15 a cock for the pipe, a chain secured to the handle of the cock, a sectional ring adapted to carry a curtain, suspending means for the ring at one side of the receptacle, and a closure for the receptacle adapted to be secured by the suspending means.

Signed at New York, in the county of New York, and State of New York this 18th day of June A. D. 1916.

PETER P. FIGUEROA.
